UNITED STATES PATENT OFFICE.

RODERICK J. DIXON, OF NEW BRITAIN, CONNECTICUT.

FLOOR STRUCTURE.

1,077,223.

Specification of Letters Patent.

Patented Oct. 28, 1913.

Application filed September 19, 1913. Serial No. 790,670.

To all whom it may concern:

Be it known that I, RODERICK J. DIXON, a citizen of the United States, and a resident of New Britain, in the county of Hartford, State of Connecticut, have invented 5 certain new and useful Improvements in Floor Structures, of which the following is a specification.

The object of this invention is to produce 10 a novel construction for heavy wooden floors, platforms, and the like, which permits of the use of ordinary smooth-faced lumber, at the same time providing a means for laying that lumber on the sub-structure 15 of rough flooring in such a manner that the central portions are held out of contact with the sub-structure, in order to prevent warping. Also, to provide means by which wear at the edges of the floor boards is largely 20 eliminated.

The invention is illustrated in the drawings in which—

Figure 1 is a sectional end view of a floor made in accordance with my invention. 25 Fig. 2 is a detail view of the supporting reinforce.

In the laying of heavy floors in mill construction, platforms, and the like, it has been customary to channel out the underside 30 of the surface floor boards lengthwise so that they will have a bearing only along their edges, leaving the central portions free from the sub-structure of rough flooring. This is done to prevent warping of the 35 boards. This channeling the floor boards and the necessity of selecting the boards as they are being laid, and properly positioning them with the channel side down, constitute a considerable item of expense, 40 both in the manufacture of the stock and in laying it. It has also been found that where the floor is subjected to heavy wear, especially by wheeled trucks and the like, the edges of the boards wear away more 45 rapidly than the central portions and in a short time an uneven surface is produced, necessitating replacement.

In accordance with my invention I have produced a device which permits of the use 50 of plain-faced lumber which is supported along its edges so that its central portion is out of contact with the sub-structure, and which also practically eliminates wear at the edges of the boards.

55 My device comprises what I have called a supporting reinforce, formed from a strip

of metal of uniform width, slashed at one edge at intervals, these short sections between slashes being bent at right angles to the strip and alternately on opposite sides 60 thereof, forming a T-shaped structure, the body of which extends even with the surface of the flooring and supports or reinforces the edges of the lumber, while the laterally extending spaced flanges provide 65 a support for the edges of the lumber, holding the central portions thereof out of contact with the rough flooring, producing the same effect as if the underside of the boards were channeled, yet eliminating this expense 70 both of manufacture and of selection and positioning in the laying of the floor.

In the drawings *a* denotes the sub-structure which may be of the usual construction of joists and rough planks, or rough concrete, or other material, upon which the finish floor is to be laid; *b*, the floor boards; and *c*, the supporting reinforce having the body *d*, and the laterally extending flanges *e*, *f*, which rest upon the sub-structure and support the finish floor boards along their 75 edges.

I claim as my invention:—

1. In a floor structure, the combination with a sub-structure of rough flooring, of 80 parallel rows of supporting reinforces comprising upstanding body portions provided at their lower edge with oppositely extending lateral projections resting upon said sub-structure, and finish floor boards laid 85 between said reinforces with their longitudinal edges supported on the lateral projections thereof, the surface of said boards being substantially flush with the top of said body portions.

2. In a floor structure, the combination with the rough flooring and superposed finish floor boards, of a supporting reinforce having its body interposed between the abutting longitudinal edges of the boards, with 90 its top substantially flush with the surface of the floor, and lateral flanges extending from either side of the lower edge of said body portion and adapted to underlie and form a support for the edges of said boards 95 to hold the central portion thereof out of contact with the sub-structure.

3. In a floor structure, the combination with the rough flooring and superposed finish floor boards, of a supporting reinforce having a body portion located between abutting longitudinal edges of said boards, with its 100 105 110

top substantially flush with the surface of the floor, the lower edge of said body being slit and alternately bent at right angles to the body portion to form flanges projecting from both sides of the body portion, and adapted to underlie the edges of said boards and form a support therefor, to hold the

central portion of the boards out of contact with the sub-structure.

RODERICK J. DIXON.
